UNITED STATES PATENT OFFICE.

ROBERT C. MATHES, OF NEW YORK, N. Y., ASSIGNOR TO WESTERN ELECTRIC COMPANY, INCORPORATED, OF NEW YORK, N. Y., A CORPORATION OF NEW YORK.

AMPLIFIER CIRCUITS.

Application filed November 12, 1919. Serial No. 337,565.

To all whom it may concern:

Be it known that I, ROBERT C. MATHES, a citizen of the United States, residing at New York, in the county of Bronx, State 5 of New York, have invented certain new and useful Improvements in Amplifier Circuits, of which the following is a full, clear, concise, and exact description.

This invention relates to vacuum tube circuits and more particularly it relates to 10 amplifier circuits for repeating speech frequencies without distortion.

In the patent to Colpitts No. 1,128,292, granted February 16, 1915, there is shown a 15 pair of vacuum tubes, connected in opposition or push-pull relation, as an electric wave amplifier. The push-pull connection of vacuum tubes will herein indicate the relationship shown, for example, in the above 20 patent, where the input or control electrodes are so connected to an incoming line that one control electrode is made positive when the other is made negative, and the output circuit of the tubes are so connected to an outgoing line that the increase of current in one 25 output circuit has a similar effect upon the outgoing line as a simultaneous decrease of current in the other output circuit. It has been found that the repeating qualities of

such apparatus are improved by utilizing 30 suitable impedance elements in the output circuits of the tubes. Previously, it has been customary in selecting vacuum tubes for such push-pull amplifying circuits to secure 35 tubes having as nearly identical electric characteristics as possible because if the tubes do not have identical characteristics a certain amount of distortion or imperfection of operation results. Likewise, imperfect 40 operation results from unbalance, that is, the dissimilarity of the corresponding branches of the divided circuit associated with the vacuum tubes. In practice, it is very difficult to secure vacuum tubes which 45 are identical in all respects. Even if two specimens of a lot were identical in characteristics, much time would be consumed in exhaustive tests to select that particular pair and, moreover, it is impractical to exactly

balance two sides of the divided circuit. By 50 the use of this invention, the results secured with slightly unbalanced circuits or tubes are very much improved. In a system operating in accordance with this invention, it 55 is desirable that for the particular frequency

or frequencies to be repeated an increase of space current through one tube will cause an equal and simultaneous decrease of current through the other tube. The impedance elements to be added according to this invention are designed with this end in view. 60

In its specific aspect, hereafter described in detail, this invention comprises a push-pull amplifier circuit in which high impedance elements, such as choke coils are inserted in the direct current branches of the output circuits of the amplifiers. It has been found that with such an arrangement, there is substantially no distortion of the incoming signals and the system acts in a manner 70 which would be expected if the input-output current characteristics of the tubes was linear over the whole working range of amplitude. 75

It has also been found advantageous to employ such a circuit arrangement in a multistage amplifier set, each stage of which is of the push-pull type.

This invention will be better understood by reference to the following detailed description taken in connection with the accompanying drawing, which represents the preferred circuit arrangement of this invention. 80

The drawing represents a two-stage amplifier of the push-pull type, one stage of which comprises tubes 4 and 5, the other stage of which comprises tubes 6 and 7. Heating current for the cathodes 8, 9, 10 and 11 is supplied by a battery 12. Space current for the four tubes is supplied by battery 13. Connected between the grid 14 and the cathode 8 of tube 4 is a choke coil 15. Similarly connected between the grid 16 and the cathode 9 of tube 5 is a second choke coil 17. These impedances 15 and 17 are connected across the incoming line 18 and serve to impress any incoming signals on tubes 4 and 5. The connection is such that incoming waves that make one of the grids positive make the other grid negative so that when the impedance of one of these tubes increases the impedance of the other tube decreases. 95

The direct current branch of the output circuit of tube 4 is traced from anode 21, high impedance 22, wire 23, battery 13, through ground to cathode 8. Similarly, the direct current branch of the output circuit for tube 5 may be traced from anode 24, 110

high impedance 25, wire 23, battery 13, through ground to cathode 9. Choke coils 22 and 25 should be designed to offer a very high impedance to currents of the frequencies which are to be repeated. A substantially constant current will therefore flow through the branches of the output circuits which include these coils.

The amplified signals from tubes 4 and 10 5 will therefore be confined to the paths containing condensers 27 and 28 and will consequently be impressed across the terminals of impedances 29 and 30 upon the grids 31 and 32 of tubes 6 and 7.

15 The direct current branch of the output circuit of tube 6 is traced from anode 33, impedance 34, wire 35, battery 13, through ground to cathode 10. The direct current branch of output circuit of tube 7 is traced from anode 36, impedance 37, wire 35, battery 13, through ground to cathode 11. Choke coils 34 and 37 should be designed to offer a very high impedance to the currents of the frequencies which are to be repeated 20 so that substantially constant current flows through these coils. The amplified signals from tubes 6 and 7 will therefore be confined to the circuit which includes condenser 38, primary winding 39 of transformer 40, and condenser 41. Even though the characteristics of tubes 6 and 7 are not identical, the action of the impedances 34 and 37 in confining the amplified alternating currents to the circuit traced above, tends to cause the increase in current through one tube due to a change in its grid voltage to be equal to the decrease of current in the other tube. Hence the effect induced in the 25 secondary winding of transformer 40 for 30 the positive half cycle of a symmetrical incoming wave tends to be identical in magnitude with the effect produced by the succeeding negative half cycle. With these impedances 34 and 37 omitted, this equality 35 would not exist and distortion would occur. It follows, therefore, that the amplified impulses impressed on outgoing line 43 by transformer 40 are faithful reproductions in 40 amplified form of the signals coming in from line 18.

Condensers 44 and 45, which are inserted between the incoming line and the input of the amplifier set, serve to isolate the repeating apparatus from the effects of direct current voltage sources which may be included in line 18. These condensers 44 and 45, when used, are preferably of large capacity 55 so as to offer low impedance to alternating currents passing therethrough. In case it is desired to prevent the repeating apparatus from amplifying signals of frequencies above the essential range to be repeated, inductances 46 and 47 may be included in series with line 18 in order to choke out these 60 undesired frequencies while allowing the es-

sential range of frequencies to pass therethrough.

It is to be noted that the cathodes and the midpoints of impedances 15 and 17, 22 and 25, 29 and 30 and 34 and 37 are 70 grounded. This grounding is to prevent any undesired transfer of energy from one part of the repeater circuit to another part through capacities to ground from causing the apparatus to howl or sing. 75

It is to be understood that this invention may be variously modified without departing in any way from the spirit of this invention as defined in the appended claims.

What is claimed is:

1. In an electric system, a plurality of oppositely connected vacuum tubes each having a cathode, and a connection to ground for said cathodes for preventing said tubes from singing. 80

2. An amplifying system comprising a plurality of oppositely connected vacuum tubes, each comprising a cathode, an anode, and a control electrode, a connection between two of said cathodes and ground, and a symmetrical conducting path from ground to each of said control electrodes for preventing said tubes from singing. 85 90

3. An amplifying system comprising divided input and output circuits, electrodes connected to said output circuits, means for producing two ionized streams, said streams being connected in opposition, a control element for controlling each of said streams, a connection between one of said electrodes and ground, and a symmetrical conducting path from ground to each of said control elements for preventing energy from said output circuits from being fed back into said input circuits. 100 105

4. An amplifying system comprising a plurality of oppositely connected vacuum tubes, each comprising a cathode, an anode and a control electrode, a connection between two of said cathodes and ground, and a symmetrical conducting path from ground to each of said control electrodes, each of said paths containing an inductance of high impedance for waves of all frequencies to be amplified. 110 115

5. An electric system comprising a plurality of vacuum tube repeaters connected in opposition, each of said vacuum tubes having a cathode, an incoming line, and a conducting path in shunt to said line comprising two similar impedances, said cathodes and the common point of said impedances being grounded. 120

6. In combination, an incoming line, a condenser and a choke coil in series with each side of said line, two vacuum tube repeaters connected in opposition and each comprising a cathode, an anode and a control electrode, said control electrodes being individually connected to said line. 125 130

7. An electric system comprising a plurality of oppositely connected vacuum tubes each of said tubes comprising a cathode, an anode and a control electrode, a symmetrical 5 conducting path from ground to each of said control electrodes, and a symmetrical conducting path from ground to each of said anodes. 10
8. In an electric system, a pair of oppositely connected vacuum tubes each having input circuits and output circuits, and grounded points in said input circuits and said output circuits for preventing any unbalance of said tubes with respect to one 15 another from causing said tubes to sing. 15
9. A multistage amplifying set comprising a pair of oppositely connected vacuum tubes in each stage, each of said tubes having an anode, a cathode and a control electrode, a symmetrical conducting path from ground to each of said control electrodes, and a symmetrical conducting path from ground to each of said anodes, each of said 20 paths comprising an inductance of high impedance for waves of all frequencies to be 25 repeated. 25
10. A multi-stage vacuum tube set, each of a plurality of said stages comprising means for producing two electron streams, the streams of each of said stages being connected in opposition, and coupling means between two of said stages comprising a condenser. 30
11. A multi-stage vacuum tube set, each of a plurality of said stages comprising means for producing two electron streams, the streams of each of said stages being connected in opposition, and coupling means between two of said stages comprising a high 35 impedance shunt and a series condenser. 40
12. A multi-stage repeating set comprising two vacuum tubes connected in opposition in each of a plurality of said stages, each of said vacuum tubes having an anode, a cathode and a control electrode, one of said stages having an output circuit comprising a path between said anodes of high impedance to alternating current, and low impedance to direct current, and a path between its anodes of high impedance to direct current, and low impedance to alternating current. 45
13. A multi-stage repeating set comprising two vacuum tubes connected in push-pull relation in each of a plurality of said stages, one of said stages having an output circuit having certain portions thereof common and other portions individual to the tubes of the stage, an inductance in each of said individual portions, and a by-pass around said inductances comprising a condenser. 55
14. A multi-stage repeating set comprising two vacuum tubes connected in opposition in each of a plurality of said stages, each of said stages having an output circuit 60
- with portions in common and other portions individual to the tubes in one stage, a high impedance in each of said individual portions, a source of voltage, and a connection from a point intermediate said impedances 70 in each of a plurality of said stages to said source. 75
15. A vacuum tube repeater comprising two vacuum tubes connected in opposition, input and output circuits therefor, said output circuit comprising a simple circuit for alternating currents, a divided circuit for direct currents, and a choke coil in each branch of said divided circuit, said choke coils having separate cores. 80
16. A vacuum tube repeating system comprising two vacuum tubes connected in opposition, an output circuit for said tubes having portions individual and other portions common to said tubes, and a high inductance in each individual portion of said output circuit, said inductances being designed and positioned to have negligible mutual inductance therebetween. 85
17. A vacuum tube repeating system comprising two vacuum tubes connected in opposition, an output circuit for said tubes having portions individual and other portions common to said tubes, a high inductance in each of said individual portions, said inductances being adjusted and positioned to have negligible mutual inductance therebetween, an outgoing line, and a transformer for impressing the repeated currents upon said line. 90
18. A vacuum tube repeating system comprising two vacuum tubes connected in opposition, input and output circuits therefor, each of said tubes comprising an anode, a cathode and a control electrode, means for impressing an alternating current wave upon said control electrodes, a direct current path between said cathodes and said anodes, said path comprising portions in common and other portions individual to said tubes, and means in said path presenting substantially the same high impedance to alternating currents when said anodes are both positive with respect to a point in said common portion as when one of said anodes is positive and the other negative for alternating currents with respect to said point. 105
19. In combination, a push-pull repeater, a second push-pull repeater, and a condenser coupling for connecting the output of said first repeater to the input of said second repeater. 110
20. In combination, a push-pull repeater, a second push-pull repeater, each of said repeaters comprising a plurality of anodes and a plurality of cathodes, a connection from an anode of the first repeater to the control electrode of the second repeater comprising a capacity, a connection from a second anode of the first repeater to another control elec- 115
- 120
- 125
- 130

- trode of the second repeater comprising a second capacity, and shunt paths connecting corresponding terminals of said capacities, each of said paths comprising a high impedance.
21. An electric system comprising divided input and output circuits, electrodes connected to said output circuit, a common source of voltage for producing two ionized streams in push-pull relation between said electrodes, and a retard coil of high impedance to alternating currents connected in series with said source in each of the separate portions of said output circuit, said retard coils being designed and positioned to have negligible mutual inductance therebetween.
22. A multistage amplifier set comprising a push-pull repeater in each of a plurality of said stages each of said push-pull repeaters having a control electrode and an output circuit, a common source of voltage for said output circuits a retard coil of high impedance to alternating currents connected between said source and each of said push-pull repeaters, and means for preventing direct current voltage from said source as applied to one stage from being impressed upon the control electrodes of the succeeding stage.
23. In combination, a plurality of vacuum tubes connected in push-pull relation, a common source of space current for said tubes, and means to prevent alternating current from one side of said repeater from flowing into the portion of the space current circuit common to both sides of said repeater.
- In witness whereof, I hereunto subscribe my name this 3rd day of November A. D., 1919.

ROBERT C. MATHEIS.
